UNITED STATES PATENT OFFICE.

FORREST J. COUCH, OF SPENCERPORT, NEW YORK, ASSIGNOR TO THE AMERICAN LAUNDRY MACHINERY COMPANY, OF CINCINNATI, OHIO, A CORPORATION OF OHIO.

PRESSING-MACHINE.

1,364,253.

Specification of Letters Patent.

Patented Jan. 4, 1921.

Application filed March 23, 1917. Serial No. 156,936.

To all whom it may concern:

Be it known that I, FORREST J. COUCH, a citizen of the United States, residing at Spencerport, in the county of Monroe and State of New York, have invented certain new and useful Improvements in Pressing-Machines, of which the following is a specification.

This invention relates to pressing machines, and more particularly to what are known as sleeve stickers. Machines of this kind are used for ironing and thereby sticking together the sleeves of laundried shirts, to do away with the insertion of buttons and yet hold the cuffs in the desired curved flaring form. The invention is an improvement upon the machine described and claimed in an application of Dana H. Benjamin for pressing machine filed Mar. 12, 1917, Serial No. 154,211.

The object of this invention is to provide a duplex machine capable of taking care of two sleeves at the same time but independently of each other, and which machine is provided with improved means for guiding the sleeves to correct position between the pressing members and holding them in such position while pressing. Further objects of the invention are to provide improved heating means for the pressing members, to simplify the sleeve guiding and holding devices and generally to simplify and improve the operating mechanism.

Other objects of the invention are in part obvious and in part will appear more in detail hereinafter.

The invention comprises the construction and arrangement of parts hereinafter described and claimed.

In the drawings, which represent one embodiment of the invention, Figure 1 is a front elevation, showing the press closed; Fig. 2 is an elevation, on a larger scale, of one of the movable presser member arms; Fig. 3 is an elevation from the right in Fig. 2; Fig. 4 is a bottom plan view of the presser member arm; Fig. 5 is a cross section on the line 5—5, Fig. 2; Fig. 6 is a side elevation of the entire machine; Fig. 7 is a plan view of the sleeve guiding member; Fig. 8 is a detail cross section on the line 8—8, Fig. 1; Fig. 9 is a plan view of the stationary pressing member, the sleeve guide

being omitted; and Fig. 10 is an end view from the right in Fig. 9.

55

The machine shown in the drawings comprises a suitable frame shown as a hollow pedestal 1 mounted upon a base 2 and provided at its upper end with a platform or support 3 for the stationary pressing member 4. The latter is a hollow rectangular member extending forwardly from the support 3 and having plane surfaced side ironing faces 5 and a flat top 6. The cavity 7 in said member communicates with a steam supply pipe 8, the steam from which circulates around a vertical baffle wall 9 to an outlet passage 10 through the foot 11 which rests on the pedestal, and which outlet delivers the steam to a pipe 12. The steam circulation through said member consequently evenly heats both of the opposite ironing faces 5.

The ironing faces 5 on member 4 cooperate separately with two movable pressing members, each provided with its own suitable operating mechanism. As both of said members are alike, description of one will suffice for both. Each member, as shown, comprises an arm 13 having trunnions 14 mounted to turn in suitable supports, and provided with a head 15 having a padded pressing face 16 lying opposite to and parallel with one of the ironing faces 5. Head 15 is preferably also heated, for which purpose its inner cavity or chamber 17 communicates with two passages 18 in said arm, one of which leads out through one trunnion 14 by way of a swing joint 19 to the steam supply pipe 12, while the other leads 90 out through the other trunnion to another swing joint 20 in pipe 21. Pipe 12 has two branches 12^a and 12^b one leading to each of the two arms 13, while the two discharge pipes 21 run parallel to each other to the rear of the machine and join in a single outlet pipe 22. The steam circulation described enables the stationary and movable pressing members to be heated from the same steam source and without interference 100 with the operation of the mechanism.

The movable pressing members may be operated in any suitable manner. As illustrated, each arm 13 is provided with a seat or socket 23 opening downwardly to receive 105 the upper rounded end of a pressure rod 24

whose lower end is pivotally connected at 25 to one arm of a foot treadle 26 pivoted on the frame, coöperating with which is a release treadle 27 of common form. In the 5 rod 24 is a longitudinally yielding connection 28 to take up extra motion and prevent the application of too much pressure. Arm 13 drops by gravity to open the press whenever the release treadle 27 is operated on 10 the toggle effect of lever 26 and rod 24 is broken, the fall of the parts being cushioned by a spring 29 engaged by a collar 30 fixed on a rod 31 loosely sliding through an opening in a stationary abutment 32. A tension 15 spring 33 connects two arms 34, 35, on the arm 13 and rod 24 respectively, and maintains engagement of the upper end of the rod in the socket of arm 13.

The duplex arrangement of oppositely 20 disposed pressing members enables the operator to simultaneously work on the two sleeves of the shirt. To secure uniformly good results and to secure and hold the proper shape of cuffs while sticking together 25 the two sides of a sleeve, suitable means is preferably provided for guiding and supporting the sleeve in position to be pressed with the cuff removed from possible contact with the ironing members. The 30 means shown comprises a sleeve guiding and holding member 36 having a reinforced angle rim or wall 37 open on its front side and to which is riveted or otherwise secured a thin metal plate 38 having two narrow 35 slots 39 parallel to each other and having flaring edges 40 at their open front ends. This plate is located on the upper flat face of the stationary pressing member 4 in such 40 position that the slots 39 are located directly above the places where the stationary and movable pressing members come together, to wit, parallel with the edges of the stationary member and just above its pressing faces. 45 The member 36 is preferably detachably secured to the member 4 so that it can be readily removed when necessary to repair or replace the padding or for other reasons. As shown it is provided with several (three 50 being shown) button hole slots 41 to receive screws 42 tapped into member 4, and also has a boss 43 in which is a locking pin 44 pressed downwardly by a spring 45. When the screws 42 are fully seated in the narrow 55 portions of the button hole slots pin 44 enters a recess 46 of the member 4 and locks the plate in position. Pin 44 has a head 47 by which it may be withdrawn from its recess to release the plate. 60 In use of the machine the operator slips the sleeve through the guiding edges 40 into the proper slot 39, one of which is for left sleeves and the other for right sleeves. The facing strip along one edge of the sleeve slit is held against the plain metal face of

member 4. The cuff is above plate 38 and hence out of contact with the pressing members, and the confinement of the superposed sides of the sleeve in slot 39 gives the cuff the desirable curved flaring form. The 70 thickness of the cuff plies prevents it from being drawn down through the narrow slot and enables the operator to stretch and pull the sleeve into proper shape. Lever 26 is then depressed to move the movable pressing member into ironing relation with the stationary member and apply pressure to the work. Two sleeves can be subjected to pressure at the same time or the operator can arrange one sleeve while the other is 80 being held under ironing pressure.

It will, of course be understood that the invention is not limited to the particular construction of machine shown in the drawings but is capable of considerable modification within the scope of the claims without departing from the spirit of the invention.

What I claim is,—

1. A sleeve press, comprising a stationary pressing member having two pressing faces, 90 movable pressing members coöperating with said faces, and sleeve guiding means also co-operating therewith.

2. A sleeve press, comprising a stationary pressing member having oppositely disposed 95 pressing faces, two movable pressing members coöperating therewith, and means for supporting the sleeves in pressing position with the cuffs beyond the pressing area.

3. A sleeve press, comprising a stationary 100 pressing member having oppositely disposed pressing faces, two movable pressing members coöperating therewith, and stationary sleeve supporting means coöperating with both of said faces.

4. A sleeve press, comprising a stationary pressing member having oppositely disposed pressing faces, two movable pressing members coöperating therewith, and a sleeve 110 supporting member having sleeve receiving slots opposite both of said faces.

5. A sleeve press, comprising a stationary pressing member having oppositely disposed pressing faces, two movable pressing members coöperating therewith, and a sleeve 115 supporting member having sleeve receiving slots opposite both of said faces, said member being detachably connected with the stationary pressing member.

6. A pressing machine, comprising a 120 frame, a stationary pressing member having a lateral pressing face, a movable pressing member, an arm pivoted in the frame to swing in a plane normal to the face of said stationary pressing member and carrying 125 said movable member, an operating member mounted for movement in a plane parallel to said stationary pressing face, an operating treadle, a rod operatively connected to said treadle, and a universal joint connec- 130

- tion between said rod and said swinging arm.
7. A pressing machine, comprising a frame, a stationary pressing member having a lateral pressing face, a movable pressing member, an arm pivoted in the frame to swing in a plane normal to the face of said stationary pressing member and carrying said movable member, an operating member 10 mounted for movement in a plane parallel to said stationary pressing face, an operating treadle, a rod operatively connected to said treadle, and a ball and socket joint between said rod and said swinging arm.
- 15 8. A pressing machine, comprising a frame, a stationary pressing member having a lateral pressing face, a movable pressing member, an arm pivoted in the frame to swing in a plane normal to the face of said 20 stationary pressing member and carrying said movable member, an operating member mounted for movement in a plane parallel to said stationary pressing face, an operating treadle, a rod operatively connected to said 25 treadle, a ball and socket joint connection between said swinging arm and said rod, and means for holding said ball and socket joint in operative connection.
9. A pressing machine, comprising a 30 frame, a stationary pressing member having a lateral pressing face, a movable pressing member, an arm pivoted in the frame to swing in a plane normal to the face of said stationary pressing member and carrying 35 said movable member, an operating member mounted for movement in a plane parallel to said stationary pressing face, an operating treadle, a rod operatively connected to said treadle, a ball and socket joint con-
- nection between said swinging arm and 40 said rod, and a spring for holding said ball and socket joint in operative connection.
10. A pressing machine, comprising a frame, a stationary pressing member having a lateral pressing face, a movable pressing member, an arm pivoted in the frame to swing in a plane normal to the face of said stationary pressing member and carrying 45 said movable member, an operating member mounted for movement in a plane parallel 50 to said stationary pressing face, an operating treadle, a rod operatively connected to said treadle, an open socket carried by said swinging arm, a ball carried by said rod for engagement in said open socket, and a 55 spring for holding said ball in operative engagement in said socket.
11. A sleeve press, comprising two relatively movable pressing members having vertically disposed coöperating pressing 60 surfaces, and means above said members for supporting a sleeve in pressing position therebetween.
12. A sleeve press, comprising two relatively movable pressing members having 65 vertically disposed coöperating pressing surfaces, and a horizontal plate above said members arranged to support a sleeve in pressing position with the cuff thereof beyond the pressing area. 70
13. A sleeve press, comprising two relatively movable pressing members having vertically disposed coöperating pressing surfaces, and a horizontal plate above said members having a sleeve holding slot lying 75 opposite the space between said members.

In testimony whereof I affix my signature.
FORREST J. COUCH.
